(57) **CLAIM**

The ornamental design for glass edging, as shown and described.

DESCRIPTION

FIG. 1 is a top and right front perspective view of glass edging showing my design; and,

FIG. 2 is a left side elevational view thereof, the right side elevational view being a mirror image of the side view shown.

The top glass surface shown in FIG. 1 forms no part of the claimed design.

1 Claim, 2 Drawing Sheets

FIG. I

FIG.2
